HANDCUFF

Filed Sept. 12, 1927

Inventor

A. E. Gross,

By *Clarence O'Brien*
Attorney

UNITED STATES PATENT OFFICE.

ALBERT E. GROSS, OF PALATKA, FLORIDA.

HANDCUFF.

Application filed September 12, 1927. Serial No. 219,041.

The present invention relates to an improved hand cuff such as is used by police and officers of the law in holding and leading prisoners from place to place.

I am aware of the fact that various types of hand cuffs have been patented, but after examining the same carefully, I have observed numerous structural defects and disadvantages which I have attempted to overcome in the production of what I believe to be an entirely novel structure, which is, comparatively speaking, simple in construction, efficient in operation, and such that it can be expeditiously handled in a dependable manner.

Briefly, the invention comprises an especially designed body upon which the jaws are pivotally mounted, the body being provided with a guide for accommodating a slide such as has positive operating connection with the jaws.

Other features and advantages of the invention will become more readily apparent from the following description and drawings.

In the drawings:—

Figure 1 is a side elevational view of a handcuff constructed in accordance with the invention.

Figure 2 is a similar view with portions broken away and shown in section to disclose the details more plainly.

Figure 3 is an end view with portions broken away and shown in section, to disclose the latch.

Referring now to the drawings by reference numerals, it will be observed that the reference character 4 designates generally a body which is in the form of a single metal casting which is constructed to provide a tubular guide stem 5 at one end of which is a handgrip 6. The handgrip is preferably of semi-cylindrical cross section. At the opposite end of the stem is an enlargement which is formed to provide a cylinder 7 on opposite sides of which are outstanding flanges 8 disposed in spaced parallelism. Formed on the exterior of one of the flanges as shown in Figure 3, we find a pair of outstanding ears 9 between which a spring-pressed latch 10 is pivotally mounted. The latch is shaped to project through a hole 11 for a purpose to be hereinafter described.

Pivotally mounted at 12, we find a pair of duplicate jaws 13 shaped to embrace the wrist of the prisoner. Incidentally it will be noted that the pivoted ends of the jaws are bifur-

cated and a pair of links 14 are disposed between and pivotally connected with the furcations at their outer ends. The opposite inner ends of these links are pivoted to and between a pair of similar furcations 15 on a head 16 slidably mounted in the cylinder 7. This head is formed integral with the outer end of a shaft 17 which is slidable in the guide 5. The opposite end of the shaft extends through and beyond the guide and carries a hand grip 18. The hand grip 18 as well as the aforesaid hand grip 6 is formed with a socket in which a coil spring 19 is located. The spring is thus interposed between the two hand grips and, being of the expansion type, tends to separate the hand grips.

From the foregoing description and drawings it will be seen that I have provided an exceptionally sturdy structure which is characterized by an especially designed body constructed with a guide and a stationary hand grip at one end and means at the other end providing a mounting for a pair of pivoted jaws. The body thus made provides a carrier for what is generally designated as a slide, the slide being composed of the shaft 17, the hand grip 18, and the head 16. The head, together with the links 14 constitutes a positive operating connection between the slide and the jaws. This head is formed in one side with a keeper seat as shown in Figure 3 and this seat is adapted for reception of the latch 9 before described. Thus, it will be seen that when the latch is released by pressure from the thumb, the spring 19 will serve to quickly move the hand grips 6 and 18 apart and through the medium of the slide and links connection, the jaw 13 will be opened. Thus they can be easily placed around the wrists of the prisoner, whereupon the hand grips are literally squeezed together against the tension of the expansion spring 19. This serves through the medium of the linkage to close the jaws firmly about the prisoner's wrists. As the jaws are closed, the latch again seats itself in the keeper seat to hold them in this position, thus relieving the officer of unusual strain in holding the jaws together by a manual grip. It will be noted in this connection that the spring 19 is not absolutely essential for the hand grips could be easily pulled apart. However, the spring is advantageous in that it serves to obviate such unnecessary action. Neither is the latch absolutely essential. In fact, if the

prisoner should accidentally open the latch, this would not necessarily aid him in escaping or loosening the handcuff for the grip is maintained by pressure of the officer upon the handgrip, holding the linkage firm.

The device herein described is believed to be advantageous in the following respects. It can be operated with one hand in a quick manner. It is easy to operate, is light in weight, and very durable. It is of such size that it may be carried in one pocket. If however, it is found desirable, a spring clip 20 may be provided to permit the device to be hung on the officer's belt. There are few 15 working parts, thus decidedly simplifying the structure and permitting ready repair if such is necessary. The structure is such that the device is humane and will not lacerate the prisoner's wrists. There is absolutely no 20 strain on the spring while the jaws are open. The handcuffs can be carried in an open or closed state, whichever is found desirable. As before stated, the breaking of the spring would not interfere with the working of the 25 device except that it would not be as easy to open. In fact, it is believed that, comparatively speaking, the present device embodies indispensable features and advantages such as are not found in known devices. 30 Consequently, it is thought that this invention represents a worthy contribution to the art.

As the construction and operation and advantages of the invention have doubtless been

made plain from the foregoing, a more 35 lengthy description is believed unnecessary.

While the preferred embodiment of the invention has been shown and described, it is to be understood that minor changes in shape, size and rearrangement of details coming 40 within the scope of the adjoined claim may be resorted to if desired.

I claim:—

In a structure of the class described, a body including a tubular guide stem having a 45 rigid handgrip at one end and an enlarged head at the opposite end, said head including a cylinder, on opposite sides of which are pairs of spaced parallel flanges, a pair of complementary jaws pivotally connected with 50 and located between said flanges, a shaft slideable in said guide and having a bifurcated head at one end reciprocable in said cylinder, link connections between the furcations of 55 said last named head and said jaws, the opposite end of the shaft extending through said guide and beyond said first named handgrip, a second handgrip carried by the extending end of the shaft, said hand grips 60 being disposed in spaced parallelism, and a spring surrounding said shaft and interposed between said handgrips, and a spring pressed retaining latch carried by the first named head, said heads being provided with an 65 opening and a keeper seat arranged for co-operation with the latch.

In testimony whereof I affix my signature.
ALBERT E. GROSS.
